UNITED STATES PATENT OFFICE.

WILLIAM C. CHAMBERLAIN, OF DUBUQUE, IOWA.

TOOTH-BEAM FOR HARROWS.

SPECIFICATION forming part of Letters Patent No. 627,841, dated June 27, 1899.

Application filed July 9, 1898. Serial No. 685,468. (No model.)

To all whom it may concern:

Be it known that I, WILLIAM C. CHAMBERLAIN, a citizen of the United States, residing at Dubuque, in the county of Dubuque and State of Iowa, have invented certain new and useful Improvements in Tooth-Beams for Harrows; and I do hereby declare the following to be a full, clear, and exact description of the invention, such as will enable others skilled in the art to which it appertains to make and use the same.

My invention relates to tooth-beams for harrows and to the manner of securing the teeth to the same; and it consists of certain novel constructions, combinations, and arrangement of parts, as will be hereinafter described and specifically claimed.

Considerable difficulty has been experienced in the past in providing a simple yet adequate means for securely holding the teeth in place and preventing the teeth from slipping and becoming lost and at the same time having them capable of adjustment. It is also important that the beam should be light and yet very strong. It is to accomplish these objects that my present invention is designed.

In the accompanying drawings, Figure 1 is a perspective view of my improved tooth-beam and means for securing a tooth in position upon the same. Fig. 2 is a vertical section through the same. Fig. 3 is a horizontal section. Fig. 4 is a perspective view showing the inner face of one of the clamping-plates, and Fig. 5 is a perspective view showing the outer face of one of the clamping-plates against which the harrow-tooth rests.

A in the drawings represents my improved harrow tooth-beam, which is constructed of two metal angle-bars $a a'$, preferably of half-hexagonal shape, which bars when brought together, as shown in Fig. 1, constitute an approximately hexagonal-shaped angle-beam, the bars being left separated for the admission of means for holding the teeth securely in position and for the application of means for bracing the beam. This form of tooth-beam is very strong and yet very light and has been found exceedingly practical and desirable for the purpose desired.

B B' represent clamping-plates which are applied on each side of the tooth-beam. The

plate B is similar to the plate B', with the exception that it is provided on its front face with a deep vertical groove b , within which the tooth C is seated and by which it is prevented from having a lateral movement. Both of the plates B B' are provided with transverse passages $b' b^2$, through which a tooth-bolt D passes, as shown in the drawings. 55 The clamping-plates B B' are also provided on their inner faces with angular grooves b^3 b^4 and a central projection b^5 , the former receiving the edges of the metallic bars constituting the tooth-beams and the central projections b^5 of the plates occupying the spaces between the edges of the said bars $a a'$. 60

The tooth-bolt D is formed on one end with a square or other suitable shaped eye to correspond with the shape and size of the harrow-tooth C and provided on its other end with a screw-thread on which is applied a nut d' for holding the whole structure tightly together. By this construction and arrangement the tooth-beam is securely bridged and 70 clamped, whereby the beam is considerably stiffened and strengthened.

The harrow-tooth C is notched at intervals, as at c , and the tooth resting in the vertical groove b , which groove is deep enough to 80 penetrate the horizontal grooves $b^3 b^4$, the notches will be engaged by the edges of the bars $a a'$, constituting the tooth-beam A, and thus prevent the tooth from slipping vertically.

In order to prevent the nut d' from turning, and thus allowing the parts to become loosened, I provide a lock E, which latter consists of a piece of metal having two horizontal flat portions and a flat connecting portion, 90 the connecting portion being provided with an aperture through which the bolt D passes. The nut-lock is applied on the tooth-bolt and the nut screwed up, and then the ends are turned over, one of the ends resting against 95 one side of the nut and the other resting on the side of one of the clamping-plates, as clearly shown in Fig. 2. By this construction and arrangement it will be impossible for the nut to unscrew or become loose.

Having now described my invention, what I claim as new, and desire to secure by Letters Patent, is—

1. A tooth-beam for a harrow, comprising

- in its construction two half-hexagonal bars with a space between them, in combination with clamping-plates applied on each side of the beam, each plate being provided with a 5 transverse opening and horizontal grooves on its inner face, a tooth-bolt passed through the clamping-plates and between the bars constituting the tooth-beam, said bolt being formed at one end with an opening to receive a harrow-tooth and on its other end with a screw-threaded portion, a harrow-tooth passed through the said opening of the bolt, and a nut applied on the screw-threaded end of said bolt, substantially as described.
- 15 2. A tooth-beam for a harrow, comprising in its construction two bars with a space between them, in combination with clamping-plates applied on each side of the beam, each plate being provided with a transverse opening and grooves on its inner face, one of said plates being provided on its outer face with a deep, vertical groove which penetrates the grooves on the inner face, a tooth-bolt passed through the clamping-plates, and between 20 the bars constituting the tooth-beam, said bolt being formed on one end with an opening and at its other end with a screw-threaded portion, a harrow-tooth applied in the said opening of the tooth-bolt, said tooth being provided with notches which engage the edges of the tooth-beam, and a nut applied on the screw-threaded portion of the tooth-bolt, substantially as described.
- 25 3. A tooth-beam for a harrow, comprising in its construction two bars with a space between them, in combination with clamping-plates applied on each side of the beam, each plate being provided with a transverse opening and horizontal grooves on its inner face, a tooth-bolt passed through the clamping- 30 plates and between the bars constituting the tooth-beam, said bolt being formed at one end

with an opening to receive a harrow-tooth and on its other end with a screw-threaded portion, a harrow-tooth passed through the said 45 opening of the tooth-bolt, a nut applied on the screw-threaded end of said bolt, a nut-lock provided with an aperture through which the tooth-bolt passes, the said nut-lock bearing with one of its ends upon one side of the 50 nut and with its other end upon the edge of one of the clamping-plates, substantially as described.

4. A tooth-beam for a harrow, comprising in its construction two bars with a space between them, in combination with clamping-plates applied on each side of the beam, each plate being provided with a transverse opening and grooves on its inner face, one of said plates being provided on its outer face with a deep, vertical groove which penetrates the grooves on the inner face, a tooth-bolt passed through the clamping-plates and between the bars constituting the tooth-beam, said bolt being formed at one end with an opening and 55 at its other end with a screw-threaded portion, a harrow-tooth applied in the said opening of the tooth-bolt, said tooth being provided with notches which engage the edges of the tooth-beam, a nut applied on the screw- 60 threaded portion of the tooth-bolt, and a nut-lock provided with an aperture through which the tooth-bolt passes, the said nut-lock bearing with one of its ends upon one side of the 65 nut and with its other end upon the edge of one of the clamping-plates, substantially as described.

In testimony whereof I hereunto affix my signature in presence of two witnesses.

WILLIAM C. CHAMBERLAIN.
